(57) **CLAIM**

The ornamental design for a surgical safety marker, as shown and described.

DESCRIPTION

FIG. 1 is a top plan view of a first embodiment of the surgical safety marker of the present invention;

FIG. 2 is a rear side elevation view thereof, the front side being a mirror image;

FIG. 3 is a right side elevation view thereof, the left side being a mirror image;

FIG. 4 is a top plan view of a second embodiment of the present invention which is lined for color, the bottom and sides of which are identical to the first embodiment; and,

FIG. 5 is a top plan view of a third embodiment of the present invention, with shading to show contrast only, the bottom and sides of which are identical to the first embodiment.

The bottom is flat and otherwise unornamented.
